CLAIM

The ornamental design for an open back hat, as shown and described.

DESCRIPTION

FIG. 1 is a front side elevation view of an open back hat showing the new design;

FIG. 2 is a closed back rear side elevation view thereof;

FIG. 3 is an open back rear elevation view thereof;

FIG. 4 is a front perspective view thereof;

FIG. 5 is a closed back rear perspective view thereof;

FIG. 6 is a closed back top plan view thereof;

FIG. 7 is closed back bottom plan view thereof.

FIG. 8 is a closed back left perspective view thereof; and, FIG. 9 is a closed back right perspective view thereof.

The broken lines depict environmental features that form no part of the claimed design.
